UNITED STATES PATENT OFFICE.

ERNEST G. DANIELSON, OF SAN FRANCISCO, CALIFORNIA, ASSIGNOR TO E. T. CUNNINGHAM, OF SAN FRANCISCO, CALIFORNIA.

ELECTRIC-TUBE SOCKET.

Application filed July 25, 1921. Serial No. 487,505.

To all whom it may concern:

Be it known that I, ERNEST G. DANIELSON, a citizen of the United States, and a resident of the city and county of San Francisco, State of California, have invented a certain new and useful Electric-Tube Socket, of which the following is a specification.

The invention relates to sockets for holding thermo-ionic tubes, such as are employed in radio receiving systems. Tubes of this type usually comprise a highly evacuated glass tube mounted on a brass base and containing a plate, a grid and a filament. The filament is delicate and its life is materially prolonged if the tube is mounted in such position that the filament is held vertically. Some receiving sets are mounted on vertically disposed panels and others are mounted on horizontal tables and it is an object of this invention to provide a tube mounting or socket which may be secured either to a panel or a table, to hold the tube with the filament vertical.

Tube mountings or sockets have usually heretofore comprised an insulating base having a brass or other metallic shell or socket mounted thereon to receive the metallic tube base. This combination of metallic shell and metallic base produces a capacitance which is undesirable and another object of this invention is to provide a tube socket which eliminates this undesirable capacitance and its consequent ground noises.

The invention possesses other advantageous features, some of which, with the foregoing, will be set forth at length in the following description, where I shall outline in full that form of the invention which I have selected for illustration in the drawings accompanying and forming part of the present specification.

In said drawings:

Fig. 1 is a side elevation of the socket secured to a panel and containing one type of tube.

Fig. 2 is a plan view of the socket, as when mounted on a table.

Fig. 3 is a section taken on the line 3—3, Fig. 2.

The socket or tube mounting of my invention comprises a base 4 of insulating material, preferably that known in the trade as

Bakelite, having a vertically disposed flat face 5 adapted to bear against a panel 6, to which it is held by screws 7 passing through the panel and seating in the base. The base is also provided with holes 8 through which screws may be passed to hold the mounting to a table. The base is preferably countersunk on its under surface and the marginal edge 9 thus formed is flat so that the mounting sets flat on a table. The base is provided with thickened portions 12 extending into the countersunk area which form substantial seats for the screws 7.

Secured to the base are binding posts, 13 to which the electric current leads are attached, and disposed in the countersunk area and held in place by the binding posts are flexible contact leaves 14 with which the contacts on the tube engage. By countersinking the base and arranging the contact leaves in the countersunk area, they may be flexed by the tube contacts and still remain out of contact with the table on which the socket is mounted.

Springing from the base and formed integrally therewith is a socket 15, of insulating material, preferably Bakelite, at the bottom of which the free ends of the contact leaves are disposed. These leaves are thus supported directly on the rim of the aperture in the socket 15. The socket is provided with a bayonet clutch socket 16 for locking the tube in place. The tube mounting is preferably formed of an integral piece of molded Bakelite, making it simple and durable. By making the socket portion of Bakelite instead of metal, the losses and ground noises due to the increased capacitance in the socket are eliminated.

The overhanging lip of the bayonet clutch socket is preferably reinforced by a metallic reinforcing member 17 embedded in the Bakelite and surrounding the socket.

I claim:

In a tube mounting, a socket formed of insulation material, said socket having a bayonet slot for holding the tube, and a metallic reinforcing member arranged near the slot and held in the insulating material.

In testimony whereof, I have hereunto set my hand.

ERNEST G. DANIELSON.
